(57) **CLAIM**

The ornamental design for a headset camera and telecommunications device, as shown and described.

DESCRIPTION

FIG. 1 is a front, left side, and bottom perspective view of a headset camera and telecommunications device showing our new design;

FIG. 2 is a front, right side, and top perspective view thereof;

FIG. 3 is a right side elevation view thereof;

FIG. 4 is an exploded right side elevation view thereof;

FIG. 5 is a rear, left side, and top perspective view thereof;

FIG. 6 is a top plan view thereof;

FIG. 7 is a bottom plan view thereof;

FIG. 8 is a rear elevation view thereof;

FIG. 9 is a front elevation view thereof; and,

FIG. 10 is a left side elevation view thereof.

The broken line showing of a connector in FIG. 4 is for illustrative purposes only and forms no part of the claimed design.

1 Claim, 7 Drawing Sheets
